FIG. 1

FIG. 2

INVENTOR

WILLIAM J. RILEY,
by Arthur C. Eckert, ATTORNEY.

FIG. 3

Patented June 26, 1923.

1,459,749

UNITED STATES PATENT OFFICE.

WILLIAM J. RILEY, OF ST. LOUIS, MISSOURI.

CASKET.

Application filed July 17, 1922. Serial No. 575,584.

To all whom it may concern:

Be it known that WILLIAM J. RILEY, a citizen of the United States of America, residing at St. Louis, State of Missouri, has invented certain new and useful Improvements in Caskets, of which the following is a specification.

The object of my invention is to manufacture a casket in which the body portion will be made of one piece of opaque glass, and in which the lid or cover will be made of plate glass, and in which the lid or cover can be permanently fused to the body portion of the casket. A further object is to make a light permanent casket which can be easily and cheaply made and which when in position will be impervious to moisture, heat, etc.

With this and other objects in view, my invention has relation to certain novel features of construction and arrangement of parts as will be hereinafter more fully described, pointed out in the claim and illustrated in the drawings in which—

Fig. 1 is a perspective view of a casket with the lid or cover in position, and

Fig. 2 is a longitudinal section of the casket with the lid or cover in position, and in which—

Fig. 3 is an enlarged fragmental sectional elevation of the joint between the body of the casket and the lid or cover.

Numeral 4 designates the body portion which is made of one piece of opaque glass in the conventional casket formation. Numeral 5 designates a plate glass lid or cover which has its edges beveled as best shown at 6 in Fig. 2 and, by preference is transparent. When the lid 5 is placed in the position shown in the figures the upper surface 40 is flush with the sides of the body portion of the casket. Fusing of the lid with the sides of the body portion is shown by the cross-section in Fig. 3.

What I claim and mean to secure by Letters Patent is

A casket having an opaque monolithic body portion and transparent plate glass cover, the edges of the plate glass cover being beveled and the upper edges of the body portion being beveled permitting the lid or cover to be fused to the body portion so that the surface of the lid or cover will be flush with the sides of the body portion.

In testimony whereof I affix my signature. 55

WILLIAM J. RILEY.
